United States Patent

Des. 238,701

Patented Feb. 3, 1976

238,701

LAWN AND GARDEN TRACTOR

Donald G. Haffner, Glendale, and Knud H. Hoffmeyer
and Edward J. Lazzeroni, Sr., Racine, Wis., assignors
to Jacobson Manufacturing Company, Racine, Wis.

Filed Aug. 23, 1974, Ser. No. 500,143

Term of patent 14 years

Int. Cl. D12—09

U.S. Cl. D40—5

FIG. 1 is a side perspective view of a lawn and garden tractor, showing our new design;

FIG. 2 is a left rear perspective view thereof;

FIG. 3 is a right front perspective view thereof;

FIG. 4 is a front perspective view thereof; and

FIG. 5 is a rear perspective view thereof.

We claim:

The ornamental design for a lawn and garden tractor, substantially as shown.
